UNITED STATES PATENT OFFICE.

ANDREW J. SPICER, OF PORTLAND, OREGON, ASSIGNOR TO HIMSELF AND
ALFRED S. GROSS, OF SAME PLACE.

OILER.

SPECIFICATION forming part of Letters Patent No. 298,514, dated May 13, 1884.

Application filed October 27, 1883. (No model.)

To all whom it may concern:

Be it known that I, ANDREW J. SPICER, of Portland, Multnomah county, Oregon, have invented a new and Improved Oiler, of which 5 the following is a full, clear, and exact description.

The object of the invention is to improve oilers, as hereinafter described and claimed.

Reference is to be had to the accompanying 10 drawings, forming part of this specification, in which similar letters of reference indicate corresponding parts in all the figures.

Figure 1 is a sectional elevation of part of the 15 nozzle and nozzle-pipe. Fig. 2 is a side elevation of the parts represented in Fig. 1. Fig. 3 is a sectional elevation of the entire can. Fig. 4 is a sectional elevation of the upper part of the can and part of the nozzle-pipe, and Fig. 20 5 is a side elevation of the upper part of the can and part of the nozzle-pipe.

I make the pipe *a* separately from the can *b*, and fit it to slide freely in and out of a stuffing-box, *c*, attached to the top of the can, with 25 a follower, *d*, attached to the pipe inside of the can, to be pressed down on the oil as a means of forcing oil out of the nozzle *e*, the follower being the full size of the interior cross-section of the can, and also being shaped in conformity with the conical form of the top of the can, by

preference, but not necessarily so. Under the 30 drip-cup *f*, at the top of the nozzle-pipe *a*, I arrange a coiled spring, *g*, to raise the follower quickly after each depression for working the follower as often as and as rapidly as may be required. It will be seen that by pressing on the 35 collar *h* of the nozzle with two fingers, while holding the can between said fingers and the thumb, the latter being placed under the bottom of the can and pressing down on the nozzle-pipe, the oil will be forced out of the nozzle, 40 no matter how thick and sluggish it may be, while in all other oilers of this class the oil must be melted when very thick, and particularly in cold weather, before it can be ejected.

Having thus described my invention, I claim 45 as new and desire to secure by Letters Patent—

1. The combination, with an oil-can, *b*, of the internal presser or follower, *d*, extending out toward the side of can and converging upwardly toward and made integral with the 50 discharge-pipe *a*, as shown and described.

2. The combination, with the spring-supported follower-pipe *a*, of the nozzle *e*, having the collar *h*, as and for the purpose specified.

ANDREW J. SPICER.
